UNITED STATES PATENT OFFICE.

WILLIAM CHARLES GEBHARDT, OF SAN ANTONIO, TEXAS.

AIR-COMPRESSING APPARATUS.

1,132,331.

Specification of Letters Patent. Patented Mar. 16, 1915.

Application filed March 8, 1911, Serial No. 613,094. Renewed August 19, 1914. Serial No. 857,609.

To all whom it may concern:

Be it known that I, WILLIAM CHARLES GEBHARDT, a citizen of the United States, residing in San Antonio, in the county of Bexar and State of Texas, have invented certain new and useful Improvements in Air-Compressing Apparatus, of which the following is a specification.

This invention relates to apparatus for compressing and storing air for use in air motors of various kinds, and in other apparatus where the use of compressed air is desirable.

According to this invention I employ two kinds of tanks, reservoirs or containers, one kind being called high pressure containers and the other low pressure containers. Preferably I employ a relatively large low pressure container which is directly connected with another low pressure container which I call the intermediate container and I preferably employ two high pressure containers. The number of the various kinds of containers or reservoirs may, however, be varied.

The containers are at first charged with compressed air by means of an air compressing engine driven in any suitable way as by steam, gas or electricity. Preferably the low pressure containers are charged with a pressure of 190 pounds per square inch, and the high pressure containers with a pressure of 310 pounds per square inch.

The apparatus comprises air operated driving engines which actuate the compressors that deliver compressed air to the low pressure containers, and which are operated by compressed air from the high pressure containers; and another set of compressors, which I call compounders, which are driven by said driving engines and take the air from the low pressure containers compress it and deliver it to the high pressure containers which, as before stated, supply air for actuating the driving engines. The driving engines operate driving shafts which in turn actuate the first set of compressors and also the second set of compressors or compounders. Any desired number of engines, compressors and compounders may be employed.

In starting the apparatus the compounders are at first disconnected and the engines are operated to give the heavy fly-wheels which the apparatus contains a high speed and then the compounders are connected and by forcing compressed air into the high pressure containers they serve to prolong the time of service of such containers in operating the engines.

My invention involves not only the organization of apparatus above specified, but also novel means for cooling and lubricating various parts of the apparatus, improved devices for regulating the passage of air through the system, and many details of construction which will be hereinafter fully described.

In the accompanying drawings,—Figure 1 is a diagrammatic perspective view showing my improved air compressing and storing apparatus and illustrating the apparatus which charges it with compressed air initially, and also an engine which may be connected with my air compressing and storing apparatus and driven thereby. Fig. 2 shows a side elevation of my apparatus for compressing and storing compressed air. Fig. 2^a is a detail view on an enlarged scale of certain devices employed for controlling the mechanism for cooling the air compressors and driving engines. Fig. 3 is a perspective view of one end of the apparatus. Figs. 4, 4^a and 5, 5^a are on an enlarged scale. Fig. 4 shows a side elevation of one end of the apparatus; and Fig. 4^a shows a side elevation of the opposite end thereof. Fig. 5 is a plan view of one end of the apparatus; and Fig. 5^a is a plan view of the opposite end thereof. Fig. 6 is a view on an enlarged scale partly in section and partly in side elevation showing particularly certain features of the compounders at one end of the apparatus. Fig. 6^a is a similar view of the compounders at the opposite end of the apparatus. Fig. 7 shows a transverse section on the line 7—7 of Fig. 5. Fig. 7^a is a detail view partly in section showing certain features of the cooling and lubricating devices employed in the compressors. Fig. 7^b is a detail sectional view showing certain parts of the compounders. Fig. 8 shows a trans-

verse section on the line 8—8 of Fig. 5. Fig. 9 shows a transverse section on the line 9—9 of Fig. 5. Fig. 10 is a similar view on the line 10—10 of Fig. 5, one side of the engine, however, being shown in elevation. Fig. 11 shows a longitudinal section through one of the air compressors. Fig. 12 is a detail view on an enlarged scale and in section showing particularly the construction of one of the automatic air valves employed in the air compressors. Fig. 12^a shows a transverse section on the line 12^a—12^a of Fig. 12. Fig. 13 is a view partly in elevation and partly in section showing the connection between a high pressure cylinder and an engine which drives an air compressor and illustrates particularly the construction of the throttle valve interposed in this connection. Fig. 14 is a detail view in perspective of one of the throttle valves. Fig. 15 is a detail view in perspective of the devices for regulating the flow of air to the compounders. Fig. 16 is a detail view on an enlarged scale and in section illustrating certain features of the compounders. Fig. 17 is a perspective view, with certain parts separated, of the kind of piston preferably employed in the compounders and compressors. Fig. 18 is a detail view in section of one of the air strainers and valves for admitting air to the compressors. Fig. 19 is a detail view partly in side elevation and partly in section illustrating the preferred way of connecting certain valve rods and piston rods with the eccentrics which operate them. Fig. 20 shows a transverse section on the line 20—20 of Fig. 19. Fig. 21 is a detail view of a form of pipe coupling or rod coupling which I preferably employ. Fig. 22 is a detail view of a coupling which may be employed for two pipes arranged at right angles to each other. Fig. 23 is a detail view of a coupling for four pipes. Fig. 24 illustrates how my improvements may be applied to a locomotive boiler.

In Fig. 1 I have shown diagrammatically my improved air compressing and storing apparatus A in connection with an engine B for charging it and with an engine C which 50 can be driven by compressed air taken from the apparatus A.

The charging engine B may be of any desired kind, as shown, it comprises a steam engine b, the piston rod b' of which is connected with a cross-head b² in turn connected with a fly-wheel b³ connected through a cross-head b⁴ with an air compressor b⁵. A water tank b⁶, similar to those hereinafter described, is preferably employed to supply 60 cooling fluid to the compressor, and this supply is regulated by the devices b⁷ similar to those used in other parts of the apparatus and hereinafter described.

The air compressing and storing apparatus A is only shown in outline, X indicat-

ing the low pressure air container, Y the high pressure containers, and Z the cylinders of the driving engine. A pipe a leads from the charging compressor to the low pressure container X and a branch pipe a' 70. leads from the pipe a to one of the high pressure containers Y, which latter is connected to the other high pressure container by a pipe y. Valves a², a³, a⁴ are provided in the pipes a, a' at the points indicated. 75

The engine C is of a common type and need not be described in detail. It is connected to the low pressure container X by a pipe c.

By means of the compressing engine B the 80 containers X and Y are at first all charged with compressed air at a pressure preferably of 190 pounds to the square inch. As soon as this is done, the valve a³ and also preferably the valve a² is closed and the compressing engine B is operated until the pressure in the high pressure container reaches about 320 or 330 pounds per square inch. I would here state that a pressure of 310 pounds per square inch is used in the high 90 pressure containers, but I preferably obtain a slightly greater pressure at first for a purpose hereinafter described. As soon as these desired pressures are obtained in the low pressure and high pressure containers, the 95 compressing engine B can be disconnected and only used again when it is necessary to recharge the containers.

The apparatus A comprises in addition to the high and low pressure containers, above 100 mentioned, engines for driving the air compressors which deliver to the low pressure containers and other compressors or compounders which deliver compressed air to the high pressure containers. 105

The engines for driving the compressors and compounders are indicated at Z, the compressors at D, and the compounders at E. At F is indicated what I call an intermediate or auxiliary container which is connected with the low pressure container X by the pipe x having a valve x'. This intermediate container really forms a part of the low pressure container. It is connected therewith and it is also connected in the 110 manner hereinafter described with the air compressors D, (see Fig. 7).

The apparatus A is mounted on a bed plate 1, supported on a substantial foundation 2. 120

In the apparatus shown there are four driving engines and four corresponding air compressors driven by said engines, there being two sets of driving engines and compressors on each side of the apparatus, and 125 there are also four compounders E, two at one end of the middle portion of the apparatus and two at the opposite end thereof.

Each driving engine Z is connected by a rod z⁴ with a cross-head 3 in turn connected 130

by a rod z^{10} with a crank 4 on a driving shaft 5, and each end of the two driving shafts is connected by a rod 6 with a cross-head 7 in turn connected with the piston of a compressor D. Each driving shaft 5 carries near each end two fly-wheels 8 and an intermediate relatively large fly-wheel 9 whereby the operation of the apparatus is rendered uniform and steady. The crank arm 4 is placed as close as possible to the fly-wheel.

It will be observed that there are two driving shafts, one at each end of the apparatus, and that each driving shaft operates a compressor on each side of the apparatus. Furthermore each driving shaft is connected to and operates two compounders in the manner indicated in Figs. 5, 5^a, 6, 6^a, i. e., the piston of each compounding is connected with a cross-head 10 in turn connected by a rod 13 with an eccentric strap 11 surrounding an eccentric 12 on the shaft 5.

Each driving shaft 5 is mounted in bearings formed in two standards 14 (Fig. 8) bolted to the bed plate 1. Each standard is surmounted by a removable cap 15 bolted to the standard as indicated. Annular recesses 16 are formed in the shaft in which fit semi-circular ribs 17, 18 formed on the lower portion of the cap and the upper portion of the standard, and this construction serves to prevent endwise movement of the shaft while permitting it to rotate freely. There are four such standards, two for each shaft, and they are all similarly formed. The shafts 5 are also supported by standards 19 each formed integrally and parallel with a standard 14 but separated a short distance therefrom. The bearings of the shafts 5 in the standards 19 may be suitably lubricated by oil from the cups 20 and oil may be supplied to the bearings in the standards 14 from the oil cups 21. The eccentrics 12 and strap 11 may be lubricated in the manner shown.

In order to cool each bearing I may supply water thereto in the manner shown in Fig. 8, where 22 indicates a water tank having a gage 22^a and connected by pipes 23 with the bearing. Water is supplied to each tank from a high pressure container Y by means of a pipe 24, while air is supplied to the top of the water tank by means of a pipe 25. In this way sufficient pressure is obtained to cause the water to pass through the bearings and thus keep them cool. 26 indicate passages through which the water escapes. The pipes are provided with proper valves for regulating the flow of the cooling medium. Water may be injected into the containers by injectors Y² of any suitable kind.

Each engine Z (Fig. 10) for driving a shaft 5 comprises a cylinder z, a piston z', an air chest z² and a slide valve z³ (Fig. 10).

The piston is connected by means of a rod z⁴ with one of the cross-heads 3 hereinbefore mentioned, which cross-head reciprocates in guides formed in supporting blocks z⁵ mounted on the bed plate 1. There are two such supporting blocks on each side of the apparatus and there are two similar blocks z¹⁵ on each side for the cross-heads 7. On these blocks z⁵ and z¹⁵ are mounted saddles G which assist in supporting the high pressure containers Y, these containers being also supported by saddles H on the engines Z. Saddles I are also applied to the under sides of the containers Y and these are connected by arms or braces i 80 with saddles J beneath the low pressure container X. In like manner the saddles G and H are connected with saddles K and L beneath the low pressure container and the saddles are securely fastened to the containers in the manner shown. The intermediate container F also rests in saddles M which are suitably supported as shown in Figs. 6, 6^a and 7 on the frame of the compounders E.

The slide valve z³ of each engine Z is connected by a rod 26 with an eccentric 27 on one of the driving shafts 5, and the admission of compressed air from the air chest z² to the engine is controlled in the usual way. 95 Each cylinder z is provided with an exhaust pipe z¹⁴.

Air passes from the high pressure containers Y to the four engines Z simultaneously by way of the pipes N and throttle 100 valves N', the construction and operation of which will be next described.

There are four throttle valves N' employed, one for each of the four engines Z, and they are all of the same construction 105 and operate in the same way. As shown in Fig. 14 the valve N' consists of a cylinder n having guide ribs n' on opposite sides and a port n² which extends transversely through it. The ribs n' enter corresponding grooves 110 in the cylindrical valve casing N² which is closed at opposite ends by the heads n³. The pipe N is connected with the valve casing in the manner so clearly shown in Fig. 13 as to need no further description, and this 115 casing is connected by the passage n⁴ with the air chest z² in the manner shown in Figs. 10 and 13. The valves N' at one end of the apparatus and on opposite sides thereof are connected to rods 28 which are coupled at 120 29 to rods 30 which extend through posts or standards S mounted on the bed plate. The rods 30 are screw-threaded at s and engage corresponding threads in the posts and each such rod 30 is so coupled with a rod 28 that it can turn without turning the rod 28 but will move the latter endwise. Oil may be supplied to the bearing of the rod 30 by a suitable oiling device s⁴.

The coupling 29 is preferably constructed 130

as indicated in Fig. 13, *i. e.*, it consists of two plates bolted together and suitably recessed to receive cylindrical heads s' , s^2 on the ends of the rods 28 and 30, permitting the head s^2 to turn freely therein.

Each rod 30 carries a hand wheel 31 having a handle 32 by means of which it can be turned and each rod also carries a sprocket wheel 33, said sprocket wheels being connected together by a chain 34 by which means the rods 30 can be simultaneously rotated to give endwise movement to the throttle valves to open and close them. The throttle valves at the end of the apparatus, shown in Fig. 3, are connected by rods 34^a (Fig. 5) with the throttle valves at the opposite end of the apparatus, so that by operating the hand wheels, or one of them, all of the throttle valves may be simultaneously opened or closed.

By the mechanism described the passage of compressed air from the high pressure containers Y to the engines Z can be properly controlled. The throttle valves can be lubricated from the cups n^5 or in any other suitable way.

Each throttle valve cylinder is provided with two blow-off cocks 35, each pair of cocks being connected by links 36 with a rod 37. There is a rod 37 on each side of the apparatus operated by a lever 38. Each rod 37 extends from one end of the apparatus to the other and connects the blow-off cocks of the throttle valve at one end of the apparatus and on one side thereof with the blow-off cocks of the throttle valve at the opposite end of the apparatus on the same side. By operating the two levers 38 the blow-off cocks of all four throttle valves may be simultaneously opened and closed.

In order to lubricate the engines Z, I preferably employ devices shown in Fig. 10 where T indicates an oil container located within another oil container T' formed in the casting T¹⁰ on the top of each engine Z. Each oil container connects at t with a passage t' leading to the interior of the cylinder z. T² indicates an oil gage connected with the container T and t⁶ indicates a valved pipe leading to a high pressure container Y by means of which pressure is obtained to force the oil into the engine cylinder. t⁷ indicates a pipe by means of which the oil container may be filled. The oil container T' may be filled in any suitable way and it is my intention to hold the supply of oil in the container T' in reserve and only use it when the supply of oil in the container T is exhausted. The passage of oil from the containers T, T' to the engine cylinders is controlled by the valve rods V. These rods also control the passage of water and oil to the compressors in the manner shown in Figs. 7, 7^a and 11 and reference

will be made to these cooling devices and also to their accompanying lubricating devices before describing the manner in which the rods V are operated.

As shown in Figs. 7, 7^a and 11 there is a water container T⁴ above each compressor and this is connected by pipe t¹⁵ with a water tank T⁵. A valve t¹⁶ controls the passage and a valved pipe t¹⁷ connects the upper portion of each water tank T⁵ with a high pressure container as shown on the right-hand side of Fig. 7 or with other suitable supply as indicated on the left-hand side of Fig. 7. In this way water is supplied to each container T⁴. Oil is supplied to each compressor from an oil tank T⁶ which is connected with an oil gage T²⁰ similar to that shown in Fig. 10 and a pipe t⁸ connects the oil tank with one of the high pressure containers Y. The passage of oil to the compressors is controlled by the valve rod V.

Referring now to Fig. 11, where the water container T⁴ and the oil container T⁶ are shown, it will be observed that the oil container T⁶ connects with a passage v leading to the interior of the cylinder of the compressor and passages v' connect the water container T⁴ with the interior of this cylinder. As clearly shown in Fig. 11, the rod V has two openings v² through it and when the rod is reciprocated oil is permitted to pass through the opening v. The rod V also has openings v³ adapted to register with the openings v' and permit water to pass to the cylinder of the compressor as the rod V reciprocates. Each opening v' is provided with a needle valve v⁴ having a hand wheel v⁵. By operating the needle valves the flow of water from the containers T⁴ to the cylinders of the compressors may be properly regulated.

Referring now to Fig. 10, it may be stated that the containers T' have passages extending from them to the interior of the cylinders of the engines similar to the passages v', shown in Fig. 11, and the valve rods V have openings v², v³ similar to those shown in Fig. 11 for controlling the passage of oil to the engine cylinders. The passages from the containers T' are regulated by needle valves t⁸ having hand wheels t⁴. There is a rod V on each side of the apparatus and each of these rods extends through the upper walls of the cylinder z and the cylinders of the compressors. Each rod on each side of the apparatus is reciprocated by devices shown in Fig. 2, where the rod D³, on each side of the apparatus which connects the pistons of two alining compressors, is connected with the rod V in the following manner. A lever d' is pivoted at d² to the frame of the apparatus and extends downwardly therefrom, its lower end entering a recess d³ in an enlarged portion D⁴ of

the piston rod D³. This lever is slotted at d⁴ and through the slot extends a pin d⁵ carried by the rod V. As the piston rod D³ is reciprocated the rod V is correspondingly reciprocated but has a shorter movement than the rod D³. The movement, however, is sufficient to open and close the passages from the oil and water containers to the cylinders of the engine Z and the compressors D. The construction on opposite sides of the apparatus is the same and is such that as the engines operate the rods V are simultaneously operated to supply regulated amounts of lubricating and cooling mediums to the engines and compressors.

Each cylinder Z is provided with two blow-off cocks 40, the blow-off cocks of the two engines on each side of the apparatus being connected by links 43 with a rod 41 operated by a detent lever 42. There are two detent levers 42 and two rods 41, and by means of these two levers the blow-off cocks of all four engines may be simultaneously opened and closed.

The four engines Z operate the two driving shafts 5 and these shafts are connected with the air compressors D in the manner before described. The four compressors D are located in the middle portion of the apparatus (Fig. 2) and are all of the same construction. The piston D' of each compressor is connected with a cross-head 7 operated from the driving shaft 5 in the manner before described. The cylinder D² of each compressor is supported on a base d⁶ (Fig. 11) and its heads d⁷ are provided with air inlet valves D⁵ of novel construction. Each valve D⁵ (Fig. 18) comprises a strainer 43 which communicates with a tube 44 entering a threaded socket in a cap 45 screwed into an opening in the head. This cap contains a tubular part 46 closed at its inner end but provided with side openings 47. Within the tube 46 is a valve 48 having a stem 49 projecting through the end of the tube 46 and carrying a disk valve 50 having a seat at 51. When air is drawn in from the atmosphere through the strainer it passes through the openings 47 to the cylinder of the compressors, the valves being in the position shown in Figs. 11 and 18, but when air pressure is applied against the opposite sides of the valves they will close on the seats and the valves 48 will also close the openings 47. Any suitable number of inlet valves D⁵ may be employed at each end of the compression cylinders.

At each end of each cylinder D² there is an automatic exit valve R (Fig. 12) which controls the passage of compressed air from the compressors D to the intermediate low pressure container F (Fig. 7). Each of these valves as shown in Fig. 12 is constructed as follows: The valve casing 52 is coupled

at q with a pipe Q leading to the intermediate low pressure container F and it connects at q' with the interior of the cylinder D². Each pipe Q has a valve q² by means of which the flow of compressed air to the container F may be permitted or entirely shut off. Within the casing 52 is a plunger valve 53 having a boss 54 adapted to enter the opening q' and a head 55 adapted to seat at 56. The valve 53 has openings through it at 57, and to the outer end of the valve 53 is connected by means of a short rod 59 a piston 60, the part 61 of which is formed with openings 62 through it. On the rod 59 there is an annular valve 63 which is free to slide back and forth on the rod and open and close the passages 57. The part 61 of the piston valve 60 is connected by means of a short rod 64 with a disk 65 against which presses a spring 66, the outer end of which is secured in the enlarged end portion 67 of the valve casing. An annular valve 68 is mounted on the rod 64 and is free to slide thereon and open and close the openings in the piston 61. By the construction shown, when air is forced outward from the compressors, all parts of the valve are opened and are in the condition shown in Fig. 12, but when this outward pressure is withdrawn the various ports in the valve will be closed. In this way a triple closure is effected. In order to lubricate and oil these valves I provide lubricating and oiling devices indicated at U. u represents a lubricant container which is connected by a pipe u' with a high pressure container Y in order that lubricant may be forced into the valve. The container u is connected by pipes u² with the valve casing as clearly shown. Water is conveyed from the bottom of a high pressure container by a pipe u³ to branch pipes u⁴ which deliver it to the interior of the valve casing. In this way as the shafts 5 revolve the compressors are operated to draw air into the compression cylinders through the admission valves D⁵ and compress it through the valves R into the intermediate low pressure container F. The pipes are provided with suitable valves for regulating the flow of the lubricating and cooling mediums.

In the compressors I preferably employ pistons of the kind shown in Figs. 11 and 17, the pistons shown in Fig. 17 being for use in either a compressor or a compounding. Each piston comprises a central disk 70 adapted to fit tightly the bore of the cylinder and on each side of which there is a part 71 of less diameter having an annular series of recesses 72 on its periphery and by the side of which there is a part of still less diameter having grooves 73 on its outer side, some of which extend entirely across the disk while others extend from its periphery inward and join the other grooves. On

opposite sides of the part 71 there is a disk 74 of the same diameter as the central disk 70 but each having a recess at 75 in its periphery. The parts 70, 71 and 74 are firmly connected together on the piston rods and the construction is such that while air cannot pass by the piston from one end of the cylinder to the other, cooling and lubricating mediums can enter the recesses and 10 grooves in the pistons and keep them cool and smooth when the pistons are in operation as the compressed air present will drive the water and oil through the grooves in the pistons.

15 It will now be understood how the air motors or engines Z are operated by compressed air taken from the high pressure cylinders Y, how these engines actuate the driving shafts 5, and how these driving 20 shafts 5 in turn actuate the compressors D which deliver air under pressure, say 190 pounds, into the intermediate container F which is connected with and really forms a part of the low pressure container X. It 25 will be understood that the air compressed into the intermediate container F is drawn from the atmosphere and compressed in the compressing engines D, and that the compressed air in the containers F and X may 30 be drawn out in the manner indicated in Fig. 1 to operate a motor or engine and any other desired pneumatic apparatus or device.

I will now describe how the air supply and the pressure in the high pressure containers is prolonged by means of what I call the compounders which compress air from the low pressure containers into the high pressure containers and in this way supply some of the losses therefrom in operating the engines. It will be understood, of course, that whenever it is necessary to recharge the apparatus by means of the changing engine B, shown in Fig. 1, this recharger may be resorted to; but for a time, the apparatus may be operated after having been once charged without recharging from an outside source.

As before specified, there are four compounders or air compressing engines, two at 50 each end of the middle portion of the apparatus, and the piston E' of each compounding engine is connected with a cross-head 10 in turn connected in the manner before described with an eccentric on a driving shaft 5. Each piston rod e carries a cross-head e' to which is connected a rod e² passing longitudinally through the upper wall of the cylinder E² and a rod e³ passing longitudinally through the lower wall thereof. Each piston E' is connected by a rod E⁴ with a cross-head E³ operating in suitable guides E⁵. The cross-head E³ on each side is connected to the rods e² and e³ of two alining compounders, and the pistons in the 65 two cylinders on each side of the apparatus

operate in unison. The rods e² and e³ also operate in unison, being all driven from the main driving shafts 5. Each rod e³ is formed with pockets e⁴ communicating with openings e⁵, and the rods e³ are arranged immediately below openings e⁶ in the cylinders. As the rods e³ reciprocate any water or excess of lubricant which may accumulate in the bottom of the cylinders will pass through the openings e⁶ into the pockets e⁴, and when the rods are reciprocated and the openings e⁵ pass out from the ends of the cylinder the water and lubricant contained in the pockets will pass out through the openings e⁵ into suitable receptacles e¹⁰. In this way 30 the cooling medium is being constantly taken away to give place to a fresh supply. Each rod e² is provided with an opening e⁷ which is adapted to communicate with openings e⁸ and e⁹ near opposite ends of the cylinder, which openings communicate with a water supply in the manner presently described. The construction is such that as the rods e² reciprocate water is alternately admitted through the openings e⁸ and e⁹ to the cylinders E² and serves to keep them cool. Water is conveyed to each cylinder E² from a high pressure container Y by pipes Y' and oil is conveyed through pipes Y¹⁰ from a container Y⁴ similar in construction to the oil containers hereinbefore referred to. Suitable valves are employed to regulate the flow of oil and water to the cylinders.

Each cylinder E² is provided with two blow-off cocks W and each pair of blow-off cocks is connected to levers w (see Fig. 16) which are in turn connected by rods w' (Fig. 7) to levers w² (Fig. 4) joining the rods 41 which operate the blow-off cocks of the air compressors and driving engines so that by 100 operating the two levers 42 the blow-off cocks of the driving engines, the compressors and the compounders may be simultaneously opened and closed.

The pistons E' of the compounders are 110 preferably constructed in the same manner as the pistons shown in Fig. 17 employed in the compressing engines, and these pistons being connected with the driving shafts 5 are constantly reciprocated. Each pair of compounders is connected as shown in Figs. 7, 7^b with the intermediate low pressure container F. A passage 80 extends from the bottom of the container F above the water level therein downward into the frame of 120 each pair of compressors and branches at 81^a to the middle portion of the compressors. Each passage 80 is controlled by a valve 81 preferably of the construction shown in Fig. 7 and also in Fig. 15. Each valve 81 has a 125 long pinion 82 which meshes with a spur wheel 83 on a shaft 84 which gears at 85 with a rod 86 carrying a hand operated wheel 87. By means of the hand wheel the valves 81 may be turned in either direction 130

to regulate the size of the passages connecting the intermediate low pressure cylinder with the compounders. The air drawn from the intermediate low pressure container (which is constantly being supplied by the compressors D) enters the compounders E and is forced into the high pressure containers Y. Each compoundinger is provided with a valve P of the construction shown in Fig. 16 where, as will be seen, the valve proper is arranged within a casing p having side openings p'. The end of the casing is closed by a cap p² and a spring p³ within the cap normally presses the valve P inward in such manner as to close the openings p'. It will be observed that this is an unbalanced valve, air passing from the compounders forces it open only against spring pressure and when air pressure from the compounders is withdrawn the spring automatically closes the valve. 100 indicates blow cocks for the air chests 101.

By this organization of apparatus when the high pressure cylinders are charged in the manner before described from an outside source the engines Z are operated from air derived from the high pressure cylinders to actuate the driving shafts, and these driving shafts in turn actuate the compressors D which force compressed air into the low pressure containers. These low pressure containers in turn supply air to the compounders which deliver air under increased pressure to the high pressure containers partly supplying the losses therein incident to the use of compressed air therefrom for operating the driving engines. In this way sufficient pressure can be maintained in the low pressure cylinders to supply compressed air for a considerable time to other apparatus and used for driving or operating the same.

It will be understood that the pistons of the compounders are of smaller area than the pistons of the engines and that therefore they are able to force air into the high pressure containers at an increased pressure and that the volume of compressed air thus forced into the high pressure containers is less than that drawn from these containers so that ultimately the high pressure containers will have to be recharged by the charging engine. It will also be understood that the pressure in the low pressure containers must be considerably greater than that required for operating the engine C (Fig. 1) or other motor or pneumatic device.

It has been stated in the first part of this specification that when the containers X and Y are first charged the low pressure container is preferably charged with a pressure of 190 pounds to the square inch, while the high pressure containers are charged at a pressure of 320 or 330 pounds to the square inch. In starting up the apparatus the blow-

cocks are all opened in the manner before specified so as to equalize the pressure or remove the pressure wherever required and after thus blowing through the apparatus the blow-cocks are all closed and the pressure in the high pressure containers reduced to about 310. By suitably operating the various valves the engines can be started to rotate the driving shafts, the large fly-wheels employed assisting in steadyng the movement of the shafts and carrying them beyond dead centers and also by their momentum keeping up the rotation of the shafts in case of need. In this way sufficient pressure may be maintained within the low pressure cylinders to supply power or fuel for operating various kinds of apparatus and for various other purposes.

When starting the apparatus the compounders are disconnected until the fly-wheels are gotten up to high speed. This may be done by closing the valves 81 and 101 and opening the valves 100; after this the valves 81 and 101 are opened and the valves 100 closed and the compressors are operated in the manner before described.

It will be understood that as many containers, engines, compressors and compounders as are desired may be employed. If one or more of the engines, compressors or compounders breaks down it can be shut off from the system while the others are being employed, or some of them only may be operated while others are held in reserve for emergencies. The low pressure container may be an ordinary steam boiler, but by way of illustration I have shown a low pressure container X which may be readily lifted out of the apparatus or replaced therein. After having once charged the apparatus with the compressed air such apparatus may operate for a time without recharging and thus the compressed air supplied and produced, according to my invention, may be employed in the places and under conditions where steam is usually employed. The tanks or containers are provided with suitable pressure gages F² and safety valves G², and H² indicates a whistle which may be employed.

In Figs. 19 to 23 inclusive I have shown various forms of pipe couplings and rod couplings which I prefer to employ. In Fig. 19, 200 indicates an eccentric and 201 an eccentric strap provided with arms 202 which extend between clamping plates 203. 204 indicates a rod, also extending between the clamping plates and abutting against the arms 202 at 205. The plates 203 are grooved as shown both longitudinally and transversely to receive the arms 202 and the rod 204 and also to receive collars 206, 207 on the arms and rod. Bolts 208 clamp the plates 203 together. In this way a secure connection is formed between the rod and

the arms of the eccentrics but one which would enable the rod and the eccentric to be easily separated. In Fig. 21, 209, 209^a indicate the ends of two pipe sections which join each other at 210. These are held between plates 211 which are bolted together, as shown, and are grooved both longitudinally and transversely to receive collars 212, 213 on the abutting ends of the pipes. By 10 these means the abutting ends of two pipe sections can be very securely held together and with suitable packing all danger of leaking is avoided. In Fig. 22, a somewhat similar construction is indicated for joining together the ends of two pipes 214, 215 arranged at right angles to each other. 216 indicates plates which are bolted together and which are grooved or recessed to fit collars 217, 218 on the ends of the pipes, a 15 passage 219 being formed between the ends of the pipes. If suitable packing is used, an air-tight or water-tight connection can be made but by removing the bolts the plates can be separated and the pipes disconnected. 20 In Fig. 23 I have shown how the ends of four pipes, 220, 221, 222, 223 may be connected by plates 224 grooved and bolted together in the manner before explained.

In Fig. 24 I have shown how my apparatus may be contained within a locomotive boiler. In this figure of the drawings, 300 indicates a locomotive boiler provided with a steam gage 301, and a safety valve 302. This space 300 is preferably charged with 305 compressed air at 190 pounds per square inch and compressed air may be led through the passage 303 to the cylinders of the locomotive engine to drive them by compressed air. 304 indicate the driving engines similar 35 to the engine Z hereinbefore described. 305 indicate the exhaust pipes of these engines. 306 indicate high pressure air containers which are preferably charged with compressed air at 310 pounds per square inch. 40 These high pressure containers are connected by pipe connections 307 with the throttle valves 308 which control the passage of air from the high pressure containers to the engines 304. The air compressors are 45 not illustrated, but they are similar to the air compressors D hereinbefore referred to, which air compressors are connected at 309 with the intermediate low pressure container 310. 311 indicate water tanks for 50 supplying cooling medium; they are similar to the water tanks T^a before described. 312 indicates a pipe connection between the low pressure container 300 and the intermediate container 310, this connection being provided with a valve 313. 314 indicate the eccentrics for operating the compounders which are not shown and 315 indicates a fly-wheel similar to the fly-wheel 9 hereinbefore referred to. The operation of the

apparatus is similar to the operation of the 65 apparatus shown in other figures of the drawings and hereinbefore fully explained.

Fig. 24 is merely for the purpose of showing that my apparatus may be built in a compact form and contained within a locomotive boiler to supply compressed air to the driving engines thereof.

I am aware that it is common practice when starting from a station to supply locomotive boilers with compressed air to operate 75 the engines for a time until steam of a sufficient pressure is generated, but according to my invention I store the containers of my apparatus with compressed air, utilize the pressure from the high pressure containers to operate engines which in turn operate compressors and compounders which compressors supply compressed air to low pressure containers from which compressed air is drawn to operate the locomotive engine. 80

It is well understood that it is often desirable to operate engines or motors of various kinds by air at a certain pressure—a low pressure such as 190 pounds. Where 90 high pressure is used and a sudden expansion occurs there are the objectionable features of freezing, etc. The apparatus herein before described may be used where a tank containing compressed air at a comparatively low pressure can be fed with air from another source to maintain this pressure. I employ in my apparatus high pressure cylinders which are initially charged by separate apparatus and instead of connecting these 95 high pressure cylinders directly with the low pressure cylinder and employing reducing valves, as is often done, I employ engines which are driven by air from the high pressure cylinders, suitable means being employed for reducing the pressure of the air passing from the high pressure cylinders to the engines. These engines driven from the high pressure cylinders are caused to operate compressors and these 100 compressors take air from the atmosphere, as much air, as nearly as possible, as is taken from the low pressure cylinders being taken to drive the motors, etc. This air is compressed, not into the high pressure cylinder 110 but into the low pressure cylinder. It is obvious that if this operation continues very long the pressure in the high pressure cylinders will be reduced and the engines driving the compressors will soon cease to operate. 115 I have found that the supply of compressed air in the high pressure cylinders can be maintained for a considerable time by means of the compounders, hereinbefore described, which draw air from the low pressure cylinders and compress it at the proper pressure into the high pressure cylinders, the waste from the low pressure cylinders being sup 120 125

plied from the atmosphere by the engines. Such a system will operate for a sufficient length of time for practical purposes. As an example of one way of using the invention it may be said that it may be employed for operating freight engines which are started from a station by compressed air and operated until steam in the boiler can be produced. By my improvements the en-

5 10 engine may be operated for a longer time than has heretofore been possible when using compressed air for this purpose. There are, of course, various other circumstances under which the invention may be used.

15 I have shown the best way now known to me of carrying out my improvements, but I wish it understood that the organization of apparatus and details of construction may be widely varied without departing from 20 the spirit of my invention.

I claim as my invention:

1. An air compressing and air storing apparatus, comprising a low pressure container provided with means for connecting it with apparatus to be driven, a high pressure container, an engine driven by compressed air from the high pressure container, a compressor drawing air from the atmosphere operated by said engine and compressing air into the low pressure container, and a compounding operated by said engine for forcing air under increased pressure into the high pressure container.

2. An air compressing and air storing apparatus, comprising a low pressure container provided with means for connecting it with apparatus to be driven, a high pressure container, an engine driven by compressed air from the high pressure container, a compressor drawing air from the atmosphere operated by said engine and compressing air into the low pressure container, and a compounding operated by said engine which draws air from the low pressure container and forces it under increased pressure into the high pressure container.

3. An air compressing and air storing apparatus, comprising a low pressure container from which air may be drawn to operate an engine, a motor or other pneumatic device, a high pressure container, a charging engine connected with the low pressure and high pressure containers, an engine driven by compressed air from the high pressure container, a compressor operated by said engine drawing air from the atmosphere and compressing it into the low pressure container, and a compounding operated by said engine for forcing air under pressure into the high pressure container.

4. An air compressing and air storing apparatus, comprising a low pressure container provided with means for connecting it with apparatus to be driven, a high pressure container, an engine driven by com-

pressed air from the high pressure container, a driving shaft connected with said engine, a fly-wheel on said shaft, a compressor connected with said driving shaft drawing air from the atmosphere and compressing it 70 into the low pressure container, and a compounding connected with said driving shaft for forcing air under pressure into the high pressure container.

5. An air compressing and air storing apparatus, comprising a low pressure container, a high pressure container, an engine connected with the high pressure container, means for regulating the flow of air from the high pressure container to the engine, a 80 compressor operated by said engine and connected with the low pressure container, means for controlling the passage of air from the compressor to the low pressure container, and a compounding operated by 85 said engine for forcing air under increased pressure into the high pressure container.

6. An air compressing and air storing apparatus, comprising a low pressure container, a high pressure container, an engine 90 driven by compressed air from the high pressure container, a compressor operated by said engine and compressing air into the low pressure container, a compounding operated by said engine for forcing air into the 95 high pressure container, a connection between the compounding and the low pressure container, means for opening and closing this connection, means for opening and closing the connection between the compounding 100 and the high pressure container, and automatic valves interposed between the compounding and the high pressure container.

7. An air compressing and air storing apparatus, comprising a low pressure container, a high pressure container, an engine driven by compressed air from the high pressure container, a compressor operated by said engine and compressing air into the low pressure container, a compounding connected with and receiving air from the low pressure container, means for opening and closing this connection, automatic valves in the connection between the high pressure container and the compounding and relief 110 115 valves for the compounding.

8. The combination with a locomotive boiler, of an air compressing apparatus, comprising a high pressure container, an engine driven by compressed air from the 120 high pressure container, a compressor operated by said engine and compressing air into the boiler space, a compounding operated by said engine for forcing air under increased pressure into the high pressure container, a fly-wheel connected with said engine, and a pipe connected with the boiler space for carrying compressed air to the engine cylinders.

9. An air compressing and air storing apparatus, comprising a low pressure con- 130

tainer, a high pressure container, an engine driven by compressed air from the high pressure container, a driving shaft connected with said engine, a compressor connected with said driving shaft and compressing air into the low pressure container, a compounder connected with said driving shaft for forcing air under pressure

into the high pressure container and a fly-wheel coöperating with said compounder. 10

In testimony whereof, I have hereunto subscribed my name.

WILLIAM CHARLES GEBHARDT.
